DESIGN FOR A TOBACCO PIPE

Frank J. Danilowicz, Cleveland, Ohio

Application April 12, 1946, Serial No. 128,504

Term of patent 14 years

(Cl. D85—8)

To all whom it may concern:

Be it known that I, Frank J. Danilowicz, a citizen of the United States, residing in the city of Cleveland, county of Cuyahoga, and State of Ohio, have invented a new, original, and ornamental Design for a Tobacco Pipe, of which the following is a specification, reference being had to the accompanying drawing, forming a part thereof.

Figure 1 is a side elevation of a tobacco pipe embodying my invention;

Figure 2 is a front end view of the same;

Figure 3 is a rear end view of the same;

Figure 4 is a top view of the same; and

Figure 5 is a bottom view thereof.

I claim:

The ornamental design for a tobacco pipe, substantially as shown.

FRANK J. DANILOWICZ.
